UNITED STATES PATENT OFFICE.

MAX THOMSEN AND SAMUEL E. ALLERTON, OF CHICAGO, ILLINOIS.

MUSIC-LEAF TURNER.

SPECIFICATION forming part of Letters Patent No. 511,900, dated July 2, 1895.

Application filed November 16, 1894. Serial No. 528,967. (No model.)

To all whom it may concern:

Be it known that we, MAX THOMSEN and SAMUEL E. ALLERTON, citizens of the United States, residing at Chicago, in the county of Cook and State of Illinois, have invented certain new and useful Improvements in Music-Leaf Turners, of which the following is a specification.

This invention relates to improvements in a device for turning leaves, and more especially the leaves of sheet music or musicbooks, and while it is more especially adapted to be applied to pianos, yet it is applicable also to music stands used by orchestras; and it consists in certain peculiarities of the construction, novel arrangement, and operation of the various parts thereof, as will be hereinafter more fully set forth and specifically claimed.

The objects of our invention are, first, to provide a music leaf turner, which shall be simple and inexpensive in construction, strong and durable, yet effective in operation; second, such a leaf turner which may be so applied to a piano that it will not in any way deface or mar the appearance thereof, and when not in use will be excluded from view, and, third, a music leaf turner, which may be operated by use of the knee or leg of the person performing on the piano or other instrument, thus allowing free use of the hands.

In order to enable others skilled in the art to which our invention pertains to make and use the same, we will now proceed to describe it, referring to the accompanying drawings, 35 in which—

Figure 1 is a perspective view of a portion of a piano, showing our music leaf turner in position ready for operation. Fig. 2 is a view in elevation of the upper portion of the leaf turner, showing the parts in their normal position. Fig. 3 is a plan view of the adjustable operating arm. Fig. 4 is a central vertical sectional view of the leaf turner, showing it detached from the piano and fore-shortened 45 for the convenience of illustration. Fig. 5 is a bottom plan view of the operating gears. Fig. 6 is a plan view of a segmental gear removed from the operating rod. Fig. 7 is a face or edge view of the segmental operating gear illustrated in Fig. 5. Fig. 8 is a bottom plan view of a portion of the free end of the operating arm showing the fingers to engage

the leaf of music, and the manner of their operation. Fig. 9 is a view in detail of a spring actuated clasp to hold the sheets of music in 55 the desired position after they have been turned. Fig. 10 is a sectional view of a portion of the operating arm, showing a modification in the construction and operation of the fingers. Figs. 11 and 12 are diagrammatical views, partly in section, taken on line 11, 11, of Fig. 2, illustrating the operation of the fingers of the operating arm on the sheet of music; and Figs. 13 and 14 are similar views, taken on line 13, 13, of Fig. 10, showing 60 the operation of the fingers in said modification.

Similar letters refer to like parts throughout the different views of the drawings.

A, represents an upright standard or tube, 70 which is located vertically within the piano at the rear of the key-board. This tube or standard A, has suitable bearings in the piano and extends slightly below the bottom of the key-board or desk, and has fixed on its 75 lower end a segmental cogged gear A', which is provided with an opening a, through which the operating rod B, passes. The upper portion of the standard or tube A, is united by means of an adjusting collar b, with an extension standard or tube A², which extends upward and within the recess b', in the front of the piano, for the reception of the music holder b², which may be of the ordinary or any preferred kind. The upper end of the 85 standard or tube A², is provided with a laterally extending hollow arm A³, which arm is rigidly fixed to said tube. The upper surface of the arm A³, is provided with a longitudinal slot a', for the operation of the adjusting 90 set screws a², and a³, whose functions will presently be explained.

Just below the arm A³, and on the upper portion of the tube A², is loosely located a collar D, which is provided with laterally 95 extending arms D', on the free end of each of which is located a spring actuated catch D², to hold the sheets of music in the desired position before or as soon as they have been turned. The catches D², are journaled on 100 the arms D', and are held in their normal positions by means of a spring d², which is connected at one of its ends to the arm and at its other end to the catch. The said catch

is provided with forks D³, and D⁴, both of which are curved rearwardly, so that the upper one D³, will extend to the rear and somewhat above the arm A³, when the same is in its normal position. The lower prong or fork E⁴, is provided with a cross piece or foot d³, which rests against the music leaf.

Passing through the tubes or standards A, and A², is an operating rod B, on the lower end of which is fixed a cogged gear E, which meshes with the segmental gear F, which is pivotally secured to the lower surface of the desk or key-board of the piano by means of a pin passed through its opening f. This gear is provided with an arm or extension f', which projects forwardly on the piano and is then formed at its free end with a fork f², to engage the knee or leg of the performer.

As shown in Figs 5, and 7, of the drawings, the segmental gear F, is provided on its face with gear teeth, which are arranged in sections g, g', and g². The sections g, g', and g², are adapted to mesh with the gear E, while the section g', of teeth, are designed to mesh with the gear A'. The upper end of the operating rod B, passes into the hollow of the arm A³, and is provided with a crank shaft B', to which is secured at one of its ends a rod B², which is pivotally connected at its other end to a rod B³, to the outer end of which is adjustably secured by means of a set screw a², a rod or bar B⁴, which extends into the cavity of the extension tube or arm A⁴, which is designed to telescope with the arm A³, and is adjusted thereon by means of the set or thumb-screw a³, which operates in the slot a', of the arm A³. Near its outer end the extension arm or tube A⁴, is provided with a longitudinal slot b⁵, which is for the operation of the axis h, of the finger H, which finger is movably secured in the end of the rod B⁴, and is provided on its lower portion with a rubber or elastic covering or cushion H'. The lower surface of the extension tube or arm A⁴, is formed with a longitudinal slot b⁶, one edge of which slot is provided with gear teeth b⁷, to mesh with a cogged gear h², located on the axis h, of the finger H. The lower surface of the extension tube or arm A⁴, at the inner end of the slot b⁶, therein is provided with a stationary finger H², the lower portion of which finger is also covered with rubber or an elastic cushion H'.

In Fig. 10 of the drawings, I have shown a modification in the construction and operation of the leaf clasping and turning mechanism, which consists of an extension tube or arm A⁵, which may be secured to the arm or tube A³, in the same manner, as the arm A⁴, which has just above been described. The modified construction of the arm A⁵, illustrated in Fig. 10, is provided on its upper surface with a slot b⁵, and on its lower surface with another slot b⁷, which slots are for the reception of the finger I, which finger is fixed on the end of the rod or bar B⁴, and is provided on its lower portion with a covering H',

of rubber or other elastic material. The lower surface of the arm A⁵, near the inner end of the slot b⁷, therein, is provided with a finger I', which is rigid on the arm A⁵, and also has a rubber or elastic covering. In the sides of the arm A⁵, and between the fingers I, and I', is pivotally secured a trip lever K, which extends, as shown in Fig. 10, through the slots b⁵, and b⁷, and is held in its normal position by means of a spring k, one end of which is attached to the lever and the other end to the side of the arm A⁵, as is clearly shown in the last named figure of the drawings.

From the foregoing and by reference to the drawings, it will be seen and readily understood, that when our device is in position on the piano, the horizontal arms D', having the spring actuated catches D², will be located at the upper edge of the sheets and that the feet or cross pieces d³, of said catches will normally rest against the front or face surface of the leaves, thus holding them in the desired position. The arm A³, is located just above the arm D', and the extension arm A⁴, may be adjusted to suit the width of the sheet, by means of the set screw a³; that is, the tube A⁴, carrying the fingers H, and H², may be shortened or extended by telescoping it with the tube A³, until the finger H, will be located at the outer edge of the sheet. It is obvious that the rods B³, and B⁴, may be suitably adjusted by means of their set screw a². When the arms A³, and A⁴, shall have been adjusted, as above stated, and the finger H, placed against the outer edge of the sheet of paper to be turned, the rear side surface of the arm A³, will strike against the arm D³, of one of the catches D², and will raise its lower fork D⁴, from the sheet, as will be understood by reference to Figs. 2, and 4, of the drawings.

When it is desired to turn the sheet, the knee of the performer resting in the fork f², of the arm f', on the segmental gear F, which as before stated is pivotally secured on the lower surface of the key-board or desk of the piano, may be moved to one side, when the section g, of teeth, on the gear F, will mesh with the gear E, on the rod B, causing the same to turn and through its crank shaft B', the rods B², B³, and B⁴, to draw the finger H, toward the finger H², in which operation the gear h², on the axis h, of the finger H, meshing with the teeth b⁷, in the slot b⁶, will cause the finger H, to revolve in the direction indicated by the arrow in Fig. 11. The finger H, being covered with rubber or other elastic material will adhere to the sheet L, and by reason of its revolution and its movement toward the finger H², will cause the sheet to assume the position shown by dotted lines in Fig. 11, and in the further progress and revolution of the finger H, toward the finger H², the former named finger will pass to the rear of the sheet L, thus clamping or pinching the sheet between the two fingers, as is shown in Fig. 12. The segmental gear F, is now pressed further by means of the knee of the operator, when

the section g' , of teeth will engage the segmental gear A' , rigid on the standard or tube A , which will cause the said standard carrying the arms or tubes A^3 , and A^4 , to be turned 5 to the opposite side, thus carrying the sheet with them. The sections g' , and g^2 , of the teeth on the gear F , will also engage the gear E , and cause the fingers to release the sheet after it has been turned.

10 Should it be desired to repeat the music on the sheet, before the same has been released by the fingers it can be replaced to its normal position by the reverse movement of the segmental gear F , through its knee fork, before 15 the section g^2 , of teeth mesh the gear E . In using the modification illustrated in Fig. 10, of the drawings, the same operation is observed, but the action of the fingers I , and I' , on the sheet L , is different, for the reason that 20 the finger I , does not revolve and it will not for this reason pass to the rear of the sheet, but will adhere to its front surface, and will cause it, the sheet, to bend into the position shown by continuous lines in Fig. 14, when 25 in the progress of the finger I , toward the finger I' , the former named finger will strike the upper portion of the trip lever K , which operation will force the lower portion thereof downward to the rear of the sheet and cause 30 it to be clamped between the finger and the lever K , as shown in Fig. 14, of the drawings, when the operation of turning the sheet will be the same as above described.

Having thus fully described our invention, 35 what we claim as new, and desire to secure by Letters Patent, is—

1. In a leaf turner, the combination of the main standard or tube having its bearing in the piano or stand, with a horizontal adjustable 40 arm at its top, provided on its lower surface with a fixed finger, an operating rod aligned with the main standard and extending into the said arm and provided with a crank shaft at its upper part, an adjustable and pivotally jointed 45 rod or bar aligned with the adjustable arm, and pivotally secured to the crank shaft at one of its ends, a finger secured to the other end of said rod or bar and adapted to engage the sheet, and means at the bottom of the 50 standard to turn the same and to revolve the operating rod, substantially as described.

2. In a leaf turner, the combination of the adjustable main standard or tube, with a horizontal adjustable arm at its top provided on 55 its lower surface with a fixed finger, an operating rod within the said standard and extending into said arm and provided at its top with a crank shaft, an adjustable and pivotally jointed rod or bar pivoted to the crank 60 shaft at one end, a finger having its bearings in the adjustable arm and secured to the other end of said rod or bar and adapted to engage the sheet, and means at the bottom of the standard to turn the same and to revolve the 65 operating rod, substantially as described.

3. In a leaf turner the combination of the adjustable main standard or tube, with a hol-

low horizontal arm at its top provided on its lower surface with a fixed finger, an operating rod within the said standard and extending 70 into said arm and provided at its top with a crank shaft, a jointed rod within said arm pivotally secured at one of its ends to the crank shaft, a finger having its bearings in the said arm and secured to the other end of the jointed 75 rod and adapted to engage the sheet, and means at the bottom of the standard to turn the same and to revolve the operating rod, substantially as described.

4. In a leaf turner the combination of a 80 main standard or tube, with a hollow horizontal arm at its top provided on its lower surface with a fixed finger, an operating rod within the said standard and extending into the said arm and provided at its top with a 85 crank shaft, a jointed rod within said arm, pivoted to the crank shaft, a finger having its bearings in said arm and an elastic covering, secured to the other end of the jointed rod and adapted to engage the sheet, a collar loosely 90 mounted on the upper part of the main standard and having horizontal arms provided with spring actuated catches to normally hold the sheets, and means for turning the standard and of revolving the operating rod, substan- 95 tially as described.

5. In a leaf turner the combination of the standard A , with the tube A^2 , adjustably secured thereto, the arm A^3 , secured to the top of the tube A^2 , and having the longitudinal 100 slot a' , the tube or arm A^4 , having the slot b^5 , in its upper surface and the slot b^6 , provided with gear teeth b^7 , and the finger H^2 , in its lower surface, adjustably secured to the arm A^3 , the rod B^2 pivoted at one end to the crank 105 shaft and at its other end to the rod B^3 , the rods B^3 , and B^4 , adjustably secured together within the arms A^3 , and A^4 , the finger H , having the elastic covering H' , axis h , operating in the slots b^5 , and b^6 , and the gear h^2 , on the 110 axis h , and adapted to mesh with the teeth b^7 , and means for turning the standard, and of revolving the operating rod, all constructed, arranged and operating substantially as and for the purpose set forth. 115

6. In a leaf turner the combination of the standard A , with the tube A^2 , adjustably secured thereto, the arm A^3 , secured to the top of the tube A^2 , and having the longitudinal 120 slot a' , the tube or arm A^4 , having the slot b^5 , in its upper surface and the slot b^6 , provided with gear teeth b^7 , and the finger H^2 , in its lower surface, adjustably secured to the arm A^3 , the rod B^2 , pivoted at one end to the crank 125 shaft, and at its other end to the rod B^3 , the rods B^3 , and B^4 , adjustably secured together within the arms A^3 , and A^4 , the finger H , having the elastic covering H' , axis h , operating in the slots b^5 , and b^6 , and the gear h^2 , on the 130 axis h , and adapted to mesh with the teeth b^7 , the collar D , loosely mounted on the tube A^2 , and provided with the arms D' , the spring actuated catches D^2 , secured on each end of the arms D' , and means for turning the stand-

ard and of revolving the operating rod, all constructed, arranged, and operating substantially as and for the purpose set forth.

7. In a leaf turner the combination of the standard A, with the tube A², adjustably secured thereto, the arm A³, secured to the top of the tube A², and having the longitudinal slot a', the tube or arm A⁴, having the slot b⁵, in its upper surface and the slot b⁶, provided with gear teeth b⁷, and the finger H², in its lower surface, adjustably secured to the arm A³, the rod B², pivoted at one end to the crank shaft and at its other end to the rod B³, the rods B³, and B⁴, adjustably secured together within the arms A³, and A⁴, the finger H, having the elastic covering H', axis h, operating in the slots b⁵, and b⁶, and the gear h², on the axis h, and adapted to mesh with the teeth b⁷, the collar D, loosely mounted on the tube A², and provided with the arms D', the spring actuated catches D², secured on each end of the arms D', the segmental gear A', rigidly secured to the bottom of the main standard or tube, the gear E, fixed to the bottom of the operating rod and the segmental gear F, having on its face teeth in sections to mesh with the gears A', and E, and pivotally secured to the piano or stand, and having means to engage the knee or leg of the performer, all constructed, arranged, and operating substantially as and for the purpose set forth.

8. An arm or tube having a slot in its upper and lower surfaces and provided on its lower surface with a fixed finger, a rod within said tube adapted to be moved longitudinally therein, a finger having an elastic cover, secured to the outer end of said rod and adapted to operate in said slots, substantially as described.

9. An arm or tube having a slot in its upper and lower surfaces and provided on its lower surface with a fixed finger, a rod within said tube adapted to be moved longitudinally therein, a finger having an elastic cover, movably secured to the outer end of said rod and adapted to travel with a rotary motion in said slots, substantially as described.

10. The arm or tube A⁴, having the slot b⁵, in its upper surface, and the slot b⁶, provided with the teeth b⁷, and finger H², in its lower surface, the rod B⁴, adapted to be moved longitudinally in said tube, and the finger H, secured to said rod and having the axis h, the gear h², on said axis to engage the teeth b⁷, and the elastic cover H', substantially as described.
